UNITED STATES PATENT OFFICE.

EMILE ALEXANDRE LOUIS BOURDELLES, OF ST.-DENIS, FRANCE, ASSIGNEE TO
SOCIETE ANONYME DES ETABLISSEMENTS DELAUNAY BELLEVILLE, OF
ST.-DENIS, FRANCE, A CORPORATION OF FRANCE.

MACHINE GUN.

1,402,564.

Specification of Letters Patent. Patented Jan. 3, 1922.

Application filed July 30, 1917. Serial No. 183,616.

(GRANTED UNDER THE PROVISIONS OF THE ACT OF MARCH 3, 1921, 41 STAT. L., 1313.)

To all whom it may concern:

Be it known that I, EMILE ALEXANDRE LOUIS BOURDELLES, engineer, of 1 Rue de l'Ermitage, at St.-Denis, Department of the Seine, France, citizen of the French Republic, have invented certain new and useful Improvements in or Relating to Machine Guns (for which I have obtained a patent in France, No. 502,636, on application filed November 26, 1912); and I do hereby declare the following to be a full, clear, and exact description of the invention, such as will enable others skilled in the art to which it appertains to make and use the same.

This invention relates to an improved machine gun of the type in which a portion of the gases produced by the explosion of the powder operates alone the whole series of automatic operations required or part of the said operations when firing at the will of the operator. Part of the gases pass by a vent in the usual way and acts on a piston which drives back what we call the operating fork. At the back end of the said fork, is fixed, parallel to it and in the axis of the gun, a special screw, the end of which forms the striking pin. The said screw has a long pitch and works inside the breech block which acts as a nut. When the breech block can recoil, after firing the first thing done is the extraction of the cartridge case and second, after a certain travel, the ejection of it. Later on, a rotary motion is imparted to the breech block the effect of which is to move the entire feeding belt mechanism.

Having reached the end of its backward stroke the breech block, pushed by a spring returns to its original position taking along with it the new cartridge fed and pushing it into the barrel of the gun. When the breech is locked the striking pin, if allowed to do so, still moves.

I will describe, with reference to the accompanying drawing, a construction in accordance with this invention, but I do not limit myself to the precise construction described and illustrated.

Figure 1 shows a section of the breech mechanism.

Figure 2 is a plan of a complete machine

gun, in accordance with the present invention.

Figure 3 is a sectional view of the belt actuating mechanism on line 3—3, Fig. 2. 55

Figure 4 shows a plan of the belt feed mechanism, parts being shown in section.

Figure 5 and Figure 6 illustrate the arrangement of the hooks for fixing the charging belt in position. 60

Figure 7 shows the firing mechanism and Figure 8 the cover therefor.

Figure 9 is a detail view of the winding drum for the cartridge belt.

Figure 10 is a perspective view of the ring actuating the feed mechanism and carrying the ejector finger (not shown).

Figure 11 is a perspective view of part of the breech block front end.

Figure 12 is a front view of the back stop ring. 70

Figure 13 is a section of same.

Figures 14, 15, 16 are three views illustrating three phases of the feeding mechanism. 75

Referring to the drawings, 1 represents the breech casing, 2 is the breech block, 3 is the extractor, 4 the place occupied by the ejector, 5 the ring actuating the feed mechanism, 6 the screw and striking pin, 7 the operating fork and 8 the piston which is actuated by a portion of the gases in the usual way, 9 is the regenerating spring, 10 the back stop ring and 11 the breech extension piece, 12 is the rod that connects the operating fork 7 to the driving piston 8, 13 is a roller for guiding and supporting the operating fork. These various parts are more particularly seen in Figure 1. 80

Figure 2 shows the following parts, viz: 90

the breech casing 1, a lock 14, the nuts of the butt bolts 15, the firing lever 16, 17 the butt pushes, one for each hand, 18 the firing index, 19 the cylinder lock nut and 20 the gas cylinder. 21 are the radiating ribs, 22

the barrel and 23 a clamping ring. 24 is the feed passage, 25 the gun-carriage trunnions, 26 the operating rod of the pushes, 27 the receiver for the cartridge belt, 28

the cover for the belt-feeding mechanism, 100 and 29 the operating lever, 30 are the butt handles and 31 the pivot of the belt drum.

with its two hooks. 32 is the drum, 33 the catch, 34 the brake ring and 39 a support.

Member 14, see Fig. 2, is simply a marking device for securing the cover, 28, when said cover is closed. This cover, 28, fits on top of the casing enclosing the belt actuating mechanism, and is adapted to be opened when a belt has to be replaced or removed. The lever, or handle, 29, is substantially a key by which the catches, to be hereinafter referred to, are liberated when a change of belt takes place, see Fig. 6.

The other detail figures show the additional parts to which reference will be made in the course of the explanation of the working of the weapon, amongst others being: the feed-slide 40, the admission catch 41, the safety catch 42, the retaining catch 43, the cover 44 of the firing mechanism, 20 a tumbler 45 provided with a hole into which there passes the crank-pin of a lever that causes the release of the firing pin. The other parts will be hereinafter described.

25 In a known breech chamber 1 the breech block carries at its extreme end a locking tenon 46 and an extractor 3, this extractor nearly at the end of the recoil faces in 4 the ejector device. The breech block carries also 30 two other tenons 46'' (Fig. 11) placed radially and a little behind the tenon 46; it is through the action of these tenons acting as stops that the rotation of the breech block takes place as shall be seen hereafter.

35 This breech block 2 is connected through the medium of a screw 6, the end of which forms the striking pin, to the operating fork 7, actuated by a gas piston 8 of known form. The breech block 2, when it recoils after being rotated by the screw 6 connected to the fork 7, first of all disengages the three tenons 46, 46'' provided on the breech block. The cartridge case is carried along by the extractor 3 and subsequently ejected downwards through the breech chamber. As the movement of recoil continues the breech block is displaced angularly on the screw 6. This rotation of the breech block carries with it the feed ring 5 (Figures 1 and 10).

40 This rotation of the breech block is produced as follows: when it recoils its locking tenon 46 (Fig. 11) engages into the limited groove 46¹, shown in dotted line, existing in the feeding ring 5, Fig. 10, when it reaches the bottom of said groove rotation of course follows. As is plainly shown in the feeding ring 5, two more grooves are cut 46'' on the whole length, they act as guide ways to the two longitudinal tenons

45 (46''—46'') placed radially at the back of the breech block (Fig. 11). During the recoil, these tenons pass right through the feeding ring 5 and the stop ring 10 placed directly at the back of feeding ring 5 and 50 in which two grooves a—a are equally cut

corresponding exactly to the grooves in feeding ring 5. This stop ring 10 cannot turn around so that when rotation of ring 5 takes place the two radial tenons of the breech block are no more opposite the grooves and 55 when the return stroke begins the resistance of stop ring 10 to the motion of the tenons produces a rotation backward of the feeding ring till the tenons can pass right through again. Stop ring 10 besides, as can be seen 60 on Figs. 12, 13, can retard the motion of the breech block towards the end of its forward stroke a tenon 52 at the extreme end of the breech block sliding on an incline inside the stop ring. I may add that the feeding 65 ring 5 carries besides the cam 47 a finger, not shown, which is the ejector proper. The rotation of ring 5, in both directions, being understood I must add that the cam 47 fixed to it can move the slide 40 an amount 70 sufficient to displace the feeding belt one notch; the catch 41 is the piece acting on the belt. The safety catch 42 which keeps the feeding belt in its place has been previously 75 disengaged by the action of the tenon 49, 80 which is virtually integral with the slide 40. This tenon presses on the inclined face of a lever 50, which is capable of oscillating about the common axis 51 of the two catches. The catch 43 is disengaged by the mere 85 thrust of the belt itself. Springs are provided which tend always to keep the catches engaged. The breech block at the extreme 90 end of its recoil begins its forward stroke pushed by the spring 9. In the initial part 95 of its return stroke it is caused to rotate as we have seen in order to bring the feeding ring 5 back into the discharging or firing position shown in Figure 3. This movement displaces the belt through the necessary 100 distance so as to cause a cartridge to take up a position in front of the chamber. The belt having thus been brought into position for the insertion of a new cartridge into alignment with the barrel, becomes automatically locked again by the catches 42 and 43 which are pushed by the respective 105 springs. The fork 7 continues to advance and then carries along the movable head, which pushes before it by its upper tenon 110 46, the cartridge which it disengages from the belt.

In order to follow easily the working of the feeding device, I give the three Figures 14, 15, 16 illustrating three phases of the 115 motion of the feeding belt and showing the corresponding positions of the catch levers. As I have said near the end of the return stroke the tenon 52 limits the speed of the forward motion of the breech block; in this 120 way the shock that would be produced by its sudden stoppage against the back edge of the barrel is obviated, the screw and its striking pin, passing beyond the breech block, the latter produces the percussion. 125

The series of movements are reproduced in the same order until the supply of cartridges on the belt is exhausted.

The above description relates to the use 5 of the weapon as a continuous firing gun.

The weapon may be used also for controlled or firing at will. For this purpose, the mechanism illustrated in Figure 7 comes into play. The gunner, in this case, must 10 make use of the butt pushes 17, either right or left Figures 2 and 7 which operate the firing mechanism at will. The locking of the fork 7 is produced by a sear 54 abutting against a stop 53 cut in the said fork 15 Figure 1. This sear, 54, is rigidly connected to a platen, 55, carrying a pin 55', passing through an oval eye cut in the short lever, 45, which is part of the firing lever, 16. When the firing lever, 16, is pushed by 20 one of the rods, 17, through the pin and slot connection, 16', the pin, 55', is acted upon and the sear, 54, is thereby lowered, and the fork, 7, is released, see Fig. 1. As the firing lever continues to move, the escarpment, 56—57—58, comes into play, and by reason of the retaining cam, 57', the pawl 57, is disengaged and the spring, 59, then being under compression, as soon as the pressure is released from the push rod, 25 17, moves up the pin, 55', and with it the sear, 53. When the shot has been fired it will be necessary again to push one of the rods 17 right home in order that the firing lever 16 may again disengage the sear and 30 then bring it back to its place. That is firing at the will of the gunner. In order to pass to continuous firing all that is necessary is to place the firing index 18, which is carried by the cover 44 of the mechanism, 35 in the position shown in Figure 8. In this case a plane cut in the support of the index acts as a stop limiting the rotation of the firing lever 16 in such a way that the escapement does not work and the spring 59 cannot 40 45 raise the short lever 45. The sear 54 thus remaining inoperative the operating fork 7 is no longer arrested at 54 and the firing continues automatically.

The drum upon which the charging belt 50 is wound presents the following peculiarities.

The drum is supported by the bracket 39, upon which it is carried by a tube 60 in which a set of springs 61—62 drives a block 55 63, which terminates in the form of a cone and tends to keep apart the two rear

branches of a double catch 64—65 somewhat of the form of scissors capable of oscillating about the pivot 66.

In order to disengage the drum, all that 60 is required is to raise the branch 64 and to bring the drum forward. A new drum provided with its band is put in position, and threaded on to the two catches, which are brought near together and which lock it 65 automatically. An adjustable cone 34 is keyed on to the tube 60 upon which the drum revolves, in such a way as to act as a brake.

The feed is effected by means of charging 70 belts of 130 cartridges which are entirely of metal and very flexible. These belts are formed of steel bands 48 (Figure 4) indented at suitable intervals and in which claws, of a single piece, fixed very rigidly 75 and without any riveting, are secured.

I claim:

1. In a machine gun, a breech bolt having supporting tenons, a breech stop tenon, 80 a ring-like member having a rotary motion, and a cartridge feeding mechanism including a slide for moving the cartridge belt, the slide being actuated by the rotary motion of said ring like member.

2. In a machine gun, a rotary breech bolt 85 having supporting tenons at one end and a projection at the other end, said bolt inclosing a screw carried by the recoil mechanism and adapted to be rotated thereby, 90 means for engaging the projection to retard the return movement of the breech bolt and a cartridge feed mechanism operable to feed a cartridge under the influence of the rotary motion of the breech bolt.

3. In a machine gun, a hollow breech bolt 95 the rear end of which is adapted to inclose a screw carried by the recoil mechanism, forward end supporting tenons and a breech stop tenon carried by said bolt, a stop ring 100 for engaging said stop tenon, a ring like member surrounding said bolt and adapted to be rotated thereby, and a cartridge feed mechanism including a slide for moving the cartridge belt, the slide being actuated by the rotary motion of said ring like 105 member.

In testimony whereof I affix my signature, in presence of two witnesses.

EMILE ALEXANDRE LOUIS BOURDELLES.

Witnesses:

CHAS. P. PRESSLY,
ALEXANDRE BERTHOLET.
